OVERSHOE DISPLAY TRAY OR SIMILAR ARTICLE

William F. Lewis, Oak Park, Ill.

Application July 5, 1955, Serial No. 36,818

Term of patent 14 years

(Cl. D80—1)

Figure 1 is a plan view of the overshoe display tray or similar article, showing my new design;

Figure 2 is an end or side elevational view; and

Figure 3 is a section taken on the line III—III of Figure 1.

I claim:

The ornamental design for an overshoe display tray or similar article, as shown.
